FOREIGN PATENT DOCUMENTS

CA 2150726 12/1995

Primary Examiner — Sheryl Lane

(57) **CLAIM**

I claim the ornamental design for a tree trunk shield, as shown and described.

DESCRIPTION

FIG. 1 is a front view of the tree trunk shield.

FIG. 2 is a left side view of the claimed design.

FIG. 3 is a right side view of the claimed design.

FIG. 4 is a back view of the claimed design.

FIG. 5 is a top view of the claimed design.

FIG. 6 is a bottom view of the claimed design; and,

FIG. 7 is a perspective view of the claimed design in an open configuration.
